UNITED STATES PATENT OFFICE.

JOHN C. HOPKINS, OF LAKewood, AND ALFRED OSOLIN, OF CLEVELAND, OHIO.

MUD GUN.

Application filed February 27, 1928. Serial No. 257,306.

This invention relates to mud guns, and more particularly to mud guns for closing furnace tap-holes, and has for one of its objects the provision of an improved mud gun capable of maintaining a constant and steady pressure on the clay or other plastic material employed to stop the tap-hole.

Another object is to provide a mud gun which is safe and efficient in operation in that it is not necessary to take the blast off the furnace being worked on, and in that it is impossible for metal to blow back through the gun.

A further object is to provide a gun which will contain sufficient clay to stop the tap-hole without recharging the gun, thus eliminating the necessity of the workmen approaching the furnace while the operation of stopping the hole is in progress.

20 A still further object is to provide a mud gun having the novel construction, combination and design of parts hereinafter described and illustrated in the accompanying drawings.

25 In the drawings—

Figure 1 is a plan view, partly in section, showing a mud gun constructed in accordance with this invention, in operative position on a furnace.

30 Figure 2 is a side elevation thereof.

Figure 3 is a rear elevation thereof.

Figure 4 is a sectional plan through the gun, per se, showing the internal mechanism thereof.

35 Figure 5 is a sectional elevation taken on the line V—V of Figure 4.

Figure 6 is a transverse section taken on the line VI—VI of Figure 5.

40 Figure 7 is a fragmentary sectional plan taken on the line VII—VII of Figure 5.

Referring more particularly to the drawings, the letter A designates a portion of blast-furnace wall and the numeral 2 designates a furnace column. The furnace wall 45 A is of usual construction and has the usual iron tap-hole 3 which opens into an iron runner-trough 4.

45 A mud gun carriage B is hingedly supported on the furnace column 2. A pair of hinge-brackets 5 and 6 are secured in vertical spaced relation on the column 2 by U-bolts 7. The hinge-bracket 5 and 6 are each provided with spaced apertured hinge-lugs 7a. A hinge-shaft 8 is fixed in the apertured lugs 55 7a against rotary and vertical movement.

A carriage platform 9 is hingedly supported on the shaft 8 and is provided with a hinge member 15 journaled on the hinge-shaft 8 between hinge-lugs 7a on the lower hinge-bracket 6. A pair of supporting braces 16 and 17 are secured to the platform 9 and have their upper ends joined and journaled on the hinge-shaft 8 between the hinge-lugs 7a on the upper hinge-bracket 5.

The mud gun C, having trunnions 20, is mounted on the carriage platform 9 so as to have a swinging and pivotal movement relative thereto. A shaft 21 is rigidly mounted on the carriage 9 and projects outwardly beyond the iron runner side of the carriage. 70 A pair of bracket-arms 22 are secured in spaced relation on the projecting end of the shaft 21 and extend upwardly and forwardly on an angle toward the furnace. A pair of hanger-bars 23 are provided, one of which is pivotally connected to the upper end of each of said bracket-arms, and depend therefrom.

The lower end of the hanger-rods or bars 23 are provided with bearings in which the trunnions 20 of the mud gun C are journaled. 80 The trunnions 20 of the gun are positioned intermediate the ends of the gun at the line of balance so that the gun will be balanced on the trunnions.

A motor 25 is mounted on a motor-bracket 85 26, secured on the carriage and has its armature shaft 27 coupled to a shaft 28 of a gear reducer 29, which has a shaft 30 provided with a pinion 31. The pinion 31 is meshed with a segmental rack-member 32 which is 90 fixedly mounted on the fixed hinge-shaft 8.

When power is supplied to the motor 25 the shaft 30 and pinion 31 will be rotated and since the rack 32 is fixed, the pinion 31 will be compelled to travel around the rack and 95 will, therefore, pull or swing the platform around the hinge-shaft 8.

A vertical bracket 34 is secured to the rear corner of the carriage platform nearest the mud gun and carries a vertically disposed sheave 35 at its upper end. A horizontally disposed sheave 36 is journaled on a bracket 37 secured to the upper forward corner of the carriage 9. A cam-arm 38 is secured to the shaft 8 at a point above the rack-member 100 32. An elevator cable 39 is secured to the gun B adjacent its rear end and is trained around the sheaves 35 and 36, and over the cam-arm, and has its other end secured to the cam-arm 38.

When the carriage is swung toward the furnace, the cable 39 will be moved against the cam-arm 38 and will thereby be forced to lift or elevate the rear end of the mud gun 5 C, so as to rock the gun about the trunnions 20 and lower the forward or nose end of the gun down into line with the tap-hole 3 of the furnace A.

When the carriage is swung away from the 10 furnace, the cable 39 will be moved away from the cam-arm 38 so as to slack the tension on the cable, and the gun C will automatically be brought to a horizontal position by gravity since it is substantially balanced on its trunnions 20.

A shaft 40 is journaled on the carriage 9 and has its one end projected over the mud gun C. A pair of gun-holding dogs or arms 42 are secured to the shaft 40 and are adapted 20 to engage lugs 43 on the gun and to swing or force said gun forwardly into the iron tap-hole 3 and hold said gun in position.

A motor 45 is mounted on the carriage 9 and has its armature shaft 46 coupled to a 25 shaft 47 of a worm and worm-wheel speed reducing gearing 48 which has a shaft 49 provided with a pinion 50, which is meshed with a segmental curved rack 51 secured on the shaft 40.

30 The mud gun C to which this application is particularly directed comprises a screw conveyer housing or gun barrel 55 having a tapered nozzle 56 secured to its forward end and a gear housing 57 secured to its rear end. The gear housing 57 is closed by a cover-plate 58. The conveyer housing or barrel 55 has its upper wall stepped upwardly intermediate its ends, forming a hopper portion 59 that is provided with a hopper extension 60.

A pair of screw conveyers 61 and 62 are mounted in the barrel or conveyer housing 55 and extend from the rear end of said housing, forwardly into the nose or nozzle portion 56.

45 The screw conveyer 61 is provided with left-hand spiral flights 63 and is adapted to be rotated in a clockwise direction, while the conveyer 62 is provided with right-hand spiral flights 64 and is adapted to be rotated 50 in a counter-clockwise direction.

The conveyers 61 and 62 are adapted to force clay or other plastic material from the hopper 59 through the conveyer housing or gun barrel, and out of the nozzle 56 under pressure to plug the tap-hole of the furnace. Therefore, it is essential that there be no back flow of the clay or plastic material.

In order to prevent a back flow of the clay or plastic material, the forward end wall of 60 the hopper, at its point of juncture with the conveyer housing or gun barrel, is inclined from the side walls of the conveyer housing rearwardly and toward the longitudinal axis of the conveyer housing on an angle, as designated by the numeral 64^a, parallel with the

angle of the flights on the conveyers 61 and 62. By forming the lower end of the forward wall of the hopper on the angles, as above described, the flights on the respective conveyers will simultaneously close the space 70 between the forward edge of the hopper and the conveyer flights as said conveyers are rotated.

The upper and lower walls of the conveyer housing 55 are provided with substantially 75 wedge-shaped projections 65 and 66, respectively, immediately forward of the hopper 59, which extend into the spaces between the conveyers so as to seal said spaces and prevent a back flow of the clay under pressure 80 through these spaces.

The rear ends of the conveyers 61 and 62 are provided with threaded apertures or sockets in which shafts 67 and 68, respectively, are threaded. The shaft 67, secured 85 to the conveyer 61, is journaled in bearings 69 and 70 in the gear housing 57, and is extended, as at 71, materially beyond the gear housing, and carries a gear 72 which is meshed with the drive pinion 73 of a drive motor 74 carried by 90 the gun. The motor 74 may be powered by electricity, fluid, or any other source of power.

A pinion 75 is either formed integral with or secured to the shaft 67 and is meshed with a pinion 76 on the shaft 68, which shaft is journaled in bearings 78 and 79 in the gear housing 57.

The motor 74 is adapted to rotate the shaft 67 in a clockwise direction and consequently 100 since the shaft 67 is secured directly to the conveyer 61 the conveyer 61 will likewise be rotated in a clockwise direction, while the shaft 68 and conveyer 62 will be rotated counter-clockwise since the shaft 68 is connected directly to the conveyer 62 and is driven by the shaft 67 through the pinions 75 and 76.

The shafts 67 and 68 are provided with a thrust bearing 80 mounted between their respective pinions 75 and 76, and the cover-plate 58, forming the rear end of the gear housing 57. The bearings 80 are adapted to take up the rear thrust of the conveyers as they force the clay forward through the gun.

Throughout this specification and accompanying claims the term mud is to be construed broadly and is meant to cover clay, or any plastic material used to seal the iron or other tap-holes in furnaces or similar structures where guns of the class to which this invention belongs are used.

In operation, the hopper 59 will be filled with mud, clay or other plastic material, and the motor 74 will then be started which will rotate the shaft 67, and the shaft 68 will be caused also to rotate simultaneously through the pinions 75 and 76, thereby rotating the screw conveyers 61 and 62 simultaneously in opposite directions so as to cause the clay or other plastic material to be pulled out of the hopper 59 and forced forward through the

conveyer housing or gun barrel 55, and out through the nozzle 56.

The pressure or weight of the clay in the hopper 59, coupled with the fact that the conveyers 61 and 62 will form a vacuum as they are rotated, is sufficient to cause a steady feed of the clay to the conveyers, and the steady operation of the conveyers will cause a steady feed of clay through the gun.

10 Due to the fact that there can be no back flow of the clay through the gun, a great pressure can and is obtained at the discharge nozzle which results in the stopping of the iron tap-hole even while the blast is on in a blast-furnace.

While we have shown and described one specific embodiment of our invention, it will be understood that we do not wish to be limited thereto since various modifications may 20 be made without departing from the scope thereof, as defined in the appended claims.

We claim—

1. A mud gun for closing furnace tap-holes comprising a mud hopper, a screw conveyer housing below and communicating with said hopper, a pair of screw conveyers journaled in said conveyer housing and extending under said hopper, means in said conveyer housing forward of said hopper 30 for sealing the space between the screw conveyers so as to prevent a back flow of the mud under pressure, a nozzle on the discharge end of said conveyer housing, and means for positively rotating said screws.

35 2. A mud gun for closing furnace tap-holes comprising a mud hopper, a screw conveyer housing below and communicating with said hopper, a pair of screw conveyers journaled in said conveyer housing and extending under said hopper, one of said screw conveyers having left-hand flights and the other of said screw conveyers having right-hand flights, means in said conveyer housing forward of said hopper for sealing the 40 space between the screw conveyers so as to prevent a back flow of the mud under pressure, a gear on one of said screw conveyers, a gear on the other of said conveyers and meshed with the gear on said first named conveyer, and a motor connected to said first named conveyer and adapted to positively rotate both of said conveyers.

50 3. A mud gun for closing furnace tap-holes comprising a mud hopper, a screw conveyer housing below and communicating with said hopper, a pair of screw conveyers mounted in said conveyer housing and extending under said hopper, a shaft secured to the rear end of each of said conveyers, a gear housing secured to the rear end of said conveyer housing, said shafts being journaled in bearings in said gear housing, a gear on each of said shafts and in mesh with each other, thrust bearings on said shafts between said gears and the rear end of said gear housing, said shaft secured to the rear end of one of said conveyers being extended through said gear housing, and a motor for 55 positively rotating said shaft.

60 4. A mud gun for closing furnace tap-holes comprising a mud hopper, a screw conveyer housing below and communicating with said hopper, at least one screw conveyer mounted in said housing and extending under said hopper, the forward end wall of 65

gear housing, one of said conveyers having left-hand flights and the other of said conveyers having right-hand flights, said shaft secured to the rear end of one of said conveyers being extended through said gear 70 housing and a motor for positively rotating said shaft.

4. A mud gun for closing furnace tap-holes comprising a mud hopper, a screw conveyer housing below and communicating with said hopper, a pair of right and left-hand screw conveyers mounted side by side in parallel relation in said housing and extending under said hopper, the forward end wall of said hopper at the point of junction 80 with said conveyer housing being inclined from the side walls of the conveyor housing rearwardly and toward the longitudinal axis of said conveyer housing on an angle parallel with the angle of the flights on the respective conveyers, sealing blocks projecting from the top and bottom walls of said conveyer casing into the space between said screw conveyers immediately forward of said hopper so as to prevent a back flow of the 85 mud under pressure, a nozzle on the discharge end of said conveyer housing, and means for positively rotating said screws in opposite directions.

5. A mud gun for closing furnace tap-holes comprising a mud hopper, a screw conveyer housing below and communicating with said hopper, a pair of right and left-hand screw conveyers mounted side by side in parallel relation in said housing and extending under said hopper, the forward end wall of said hopper at the point of junction with said conveyer housing being inclined from the side walls of the conveyer housing rearwardly and toward the longitudinal axis 100 of said conveyer housing on an angle parallel with the angle of the flights on the respective conveyers, sealing blocks projecting from the top and bottom walls of said conveyer casing into the space between said screw conveyers immediately forward of said hopper so as to prevent a back flow of the mud under pressure, a shaft secured to the rear end of each of said conveyers, a gear housing secured to the rear end of said conveyer housing, said shafts being journaled in bearings in said gear housing, a gear on each of said shafts and in mesh with each other, thrust bearings on said shafts between said gears and the rear end of said gear 105 housing, said shaft secured to the rear end of one of said conveyers being extended through said gear housing, and a motor for positively rotating said shaft.

6. A mud gun for closing furnace tap-holes comprising a mud hopper, a screw conveyer housing below and communicating with said hopper, at least one screw conveyer mounted in said housing and extending under said hopper, the forward end wall of 110

said hopper at the point of junction with said conveyer housing being inclined on an angle parallel with the angle of the flights on said conveyer so that the flights on said 5 conveyer will simultaneously seal the entire length of the forward edge of the hopper and prevent back flow of the mud being

forced forward by said conveyer, and means for driving said conveyer.

In testimony whereof, we have hereunto 10 signed our names.

JOHN C. HOPKINS.
ALFRED OSOLIN.
